The figure is a perspective view of a tire showing my new design.

It is to be understood that the tread pattern as shown continues throughout the circumference of the tire and that the configuration of the opposite side of the tire is the same as that of the side shown.

The characteristic features of the tire design reside in the illustrated shape of the sidewall in combination with the novel tread pattern shown which continues into the shoulder portions of the sidewall.

I claim:

The ornamental design for a tire, substantially as shown and described.
